PHONOGRAPH PICKUP CARTRIDGE

Kenneth R. Fenne, River Forest, Ill., assignor to Motorola, Inc., Franklin Park, Ill., a corporation of Illinois

Filed Mar. 18, 1966, Ser. No. 1,540

Term of patent 14 years

(Cl. D56—4)

FIG. 2

FIG. 3

FIG. 4

FIG. 6

FIG. 5

FIGURE 1 is a top plan view of a phonograph pickup cartridge showing my new design;

FIGURE 2 is a side elevational view of the cartridge;

FIGURE 3 is a bottom plan view of the cartridge;

FIGURE 4 is a side elevational view of the cartridge showing the side opposite the side shown in FIGURE 2;

FIGURE 5 is a front elevational view of the cartridge; and

FIGURE 6 is a rear elevational view of the cartridge.

The broken line fragmentary showing of the phonograph record and pickup support arm is for illustrative purposes.

I claim:

The ornamental design for a phonograph pickup cartridge, as shown and described.
